(57) CLAIM

The ornamental design for a sports bottle holder with globe, as shown and described.

DESCRIPTION

FIG. 1 is a front elevation view of my design;

FIG. 2 is a back elevation view thereof;

FIG. 3 is a left side elevation view thereof;

FIG. 4 is a right side elevation view thereof; and,

FIG. 5 is a top plan view thereof.

Any broken line illustration of the structure in the drawing is not part of the design sought to be patented.
